UNITED STATES PATENT OFFICE.

THEODORE WINDEL, OF BROOKLYN, NEW YORK.

AUTOMATIC STABILIZER FOR AEROPLANES.

1,078,888.

Specification of Letters Patent.

Patented Nov. 18, 1913.

Application filed October 8, 1912. Serial No. 724,524.

To all whom it may concern:

Be it known that I, THEODORE WINDEL, a citizen of the United States, and resident of the borough of Brooklyn, in the county of 5 Kings and State of New York, have invented certain new and useful Improvements in Automatic Stabilizers for Aeroplanes, of which the following is a specification.

10 This invention relates to flying machines and my improvements have particular reference to means provided in conjunction with an aeroplane whereby stability thereof is automatically insured, and whereby the 15 aeroplane is caused to become automatically banked or vertically tilted toward that side of the machine describing the larger circle in making a turn, the aeroplane resuming the horizontal position upon again taking 20 a straight line of flight.

In carrying out my invention I have recourse to certain members, applied to an aeroplane, which function according to the pressures applied thereon, and which are 25 set to correct equilibrium-disturbing tendencies as and when developed.

In brief my improvement may be said to comprise a plane member, of suitable contour, pivotally supported on a flying machine in such manner that the pressure represented by a certain velocity of movement through the atmosphere will actuate said member to direct that movement of the machine in one angle, while the pressure represented by a different velocity will direct 35 the movement of the machine in a different angle.

The instrumentalities employed by me for controlling longitudinal and lateral balance 40 are of like character and arrangement, though necessarily positioned differently in the service of their respective functions. Through their means I propose to control the angle of flight solely by the speed of 45 the motor or the degree of pressure met by my special appliances, with the safety factor that if the motor should become stalled the elevator will be automatically caused to direct the machine to its normal gliding 50 angle, while maintaining the predetermined forward speed.

In the drawing: Figure 1 is a top plan view of the aeroplane having my improved stabilizing device, and with the upper supporting plane partly broken away; Fig. 2 is a side elevation of the same, and Fig. 3

is a detail of one of the balancing elevator planes.

For example I have shown my balancing or stabilizing device as applied to a bi-plane, it being obvious however that the device may also be employed with other types of flying machines. In said example *a* indicates the frame, having the usual supporting planes *b c*.

The elevator, which may be a rear elevator, is here shown as composed of two flat oval disks or planes *d e*. These disks are arranged in a horizontal plane, transversely of the frame, and are respectively supported, 60 as by rods *d' e'*, to one end of which rods they are secured, as at their under surfaces, said rods extending obliquely in opposite directions and at equal angles, opposed, from said disks, and finding pivotal engagement at their free ends in the frame, as at *d'' e''*. For purposes of reinforcement said rods may have additional supports as *d'' e''*, 70 on the frame, in which they are free to turn.

Projecting from the upper surfaces of disks *d e* respectively, are vertical, pressure receiving plates *f g*, said plates being respectively near the outer lateral edges of said disks, whereby pressure applied against the 80 forward surfaces of said plates will cause them to turn their respective disks *d e* oppositely, the inner lateral edges of said disks inclining forwardly and downwardly in this turning action. The effect is to direct 85 the aeroplane upwardly. Increased engine speed, or increased pressure upon plates *f g* will obviously accentuate the ascending angle of flight, the disks *d e* acting as ordinary elevators in this respect.

The disks *d e* are seen to be hitched together at their forward edges as by a tensional or yielding connector *h*. By means of this character the disks are normally held with their forward edges slanting slightly 90 upward, which is the correct position in starting. As pressure increases upon plates *f g* the angle of incidence of said disks changes and the machine ascends. It is my purpose to set and adjust the disks *d e* with 95 plates *f g* so that said disks will be parallel with the supporting planes when the pressure upon the plates *f g* is equivalent to a set speed, as say, 30 miles an hour. If the speed be greater than the set rate the machine will rise, if less, the machine will descend. In this manner therefore the verti- 100 105 110

cal inclination of forward travel can be controlled and regulated through the speed of the engine. In a corresponding manner I control the lateral stability of the machine with disks as i j , disposed, respectively, near opposite ends of a supporting plane. Said disks each have a supporting rod, as i' j' , said rods extending tangentially, as from the upper surfaces, respectively, of said disks, at opposite equal angles. Said rods at their free ends, are pivotally engaged with the frame, as at i^2 j^2 , and may have reinforce braces, as i^3 j^3 in which they are free to turn. The disks i j are, respectively, provided with vertical plates, as k l , which may extend rearwardly from said disks in the manner of vertical tails, or may be otherwise suitably disposed relatively to said plates. The function of the plates k l is to respond to the influence of lateral pressure, turning the disks in yielding and thereby causing the disks to direct their forward edges upwardly or downwardly as the case may be.

In the instance of the aviator swinging the rudder to make a right hand turn, for example, it is necessary that the machine be banked toward the left. This will be accomplished automatically by the pressure met by the left surfaces of plates k l , swinging said plates toward the right and thereby turning the left disk with its forward edge directed upwardly and the right disk with its forward edge directed downwardly, thus causing the machine to tilt or bank at its left side. When the rudder is straightened out again the pressure against plates k l is relieved and the machine resumes its horizontal position. Naturally the action is reversed when making a turn to the left.

Obviously an aeroplane equipped with disks like those indicated at i j will possess an unusual degree of inherent stability because the application of an excess of pres-

sure at one side of the machine, as in dropping sidewise, will cause the plates k l to swing away from that pressure, in which act the disk on the side of greater pressure will be inclined upwardly at its outer edge, while the disk on the side of less pressure will incline downwardly at its outer edge.

I claim:—

1. An aeroplane having a pair of elevator members, pivoted supports for said members arranged obliquely at opposite equal angles, a pressure influenced projection on each of said members to turn the latter, and means yieldingly restraining said members.

2. An aeroplane having a pair of elevator members, pivoted supports for said members arranged obliquely at opposite equal angles, a pressure influenced projection on each of said members to turn the latter, and means yieldingly connecting said members.

3. In an aeroplane, a supporting plane, an independently movable balance plane near one end thereof, said balance plane having a pressure plate extending at right angles therefrom, and a pivotal support for said balance plane, said support lying at an upwardly inward inclination with respect to the supporting plane.

4. In an aeroplane, a supporting plane, a pair of balance planes disposed near opposite ends thereof, a rearward, vertical, pressure plate extending at right angles from each of said balance planes, and pivotal supports for said balance planes arranged obliquely at opposite equal angles, the inclination of said supports being upwardly inward with respect to the supporting plane.

Signed at the borough of Manhattan, in the city, county, and State of New York this 7th day of October, A. D. 1912.

THEODORE WINDEL.
